UNITED STATES PATENT OFFICE

WILLIAM H. SOMMER, OF PEORIA, ILLINOIS

ARTICLE OF MANUFACTURE

Application filed March 2, 1929. Serial No. 343,954.

This invention has reference to a new and improved article of manufacture and has for its object to provide an article of, preferably soft wires, bent into desirable form to 5 adapt it to be used as a holder or retainer for packages of nails and cement in the central opening of rolls of roofing paper.

The invention has for a further object to construct such an article from a single piece 10 of wire and to shape it into a coil portion which is normally of somewhat greater diameter than the central opening of roofing rolls and retained in the interior of the roll by frictional engagement with the wall thereof 15 and with one end portion of the coil inturned transversely across the axis of the coil to provide a handle by means of which the coil may be turned to reduce its diameter for insertion into a roofing roll opening; the opposite 20 site end of the wire forming the coil being bent or inturned transversely across the axis of the coil and to a point at approximately the outside diameter of the coil and thence turned downwardly to provide a straight 25 stiffening portion considerably longer than the coil itself and thence bent inwardly at right angles to said straight stiffening portion between which and the coil, cans or packages of nails and cement may be held, supported or retained, when the article is 30 inserted into a roll of roofing paper.

That the invention may be more fully understood, reference is had to the accompanying drawings forming part of this description, 35 illustrating a preferred embodiment of the invention, in which:—

Fig. 1 shows in elevation partially in section a roll of roofing paper with my improved article of manufacture inserted therein and 40 how the same functions to retain cans or packages of nails and cement therein, and

Fig. 2 is a perspective view of the article itself.

Like characters of reference denote corresponding parts thruout the figures.

In the drawings, a roll of roofing paper is shown designated as A having the usual central opening a therethru.

Rolls of roofing paper, of the type illustrated are well known, and it is not broadly

new to provide a holder or container for supporting articles, as for instance cans or packages of nails and cement, within the opening a in such rolls. However, I have produced an article of this character, made wholly of wire which embodies a roll gripping portion and a suspended portion therefrom capable of firmly retaining or supporting cans or packages of nails or cement in superimposed relation within the central opening of the 55 roll. My improved article is designed with the idea of providing an efficient gripping portion to sustain it and the packages within the roll and a sufficiently stiff supporting or sustaining portion for the cans or packages 60 of nails and cement and one that will employ the least amount of wire consistent with its objects and purposes and which can be produced at a minimum cost and to be dispensed with, when it has served its purpose, if desired, without material loss.

The article comprises a single piece, of preferably soft wire, bent into desirable form so as to provide a coil 1 which is normally of somewhat greater diameter than the central opening a of a roll of roofing paper and from the coil depends the straight stiffening portion 2, offset from the axis of the coil and considerably longer than the coil itself, and at its lower end turned inwardly to provide the transverse rest 3, the terminal of which is looped or bent back on itself, as at 3' to obviate a sharp or tearing end. In forming the article the upper end of the coil is inturned to provide the transverse handle portion 4, by means of which the coil 1 may be turned to reduce its diameter for insertion into the opening a in the roll A, whereby to frictionally engage the wall of the opening a, as shown in Fig. 1 to sustain the article in proper placed position with respect to the length of the roll. At the lower terminal of the spring 1, the wire forming the same is inturned transversely across the base of the spring to provide a head member 5 which, at a point approximately at the outside diameter of the coil is bent downwardly to provide the straight stiffening portion 2.

Prior to insertion of the article into an opening a in a roll A, cans or packages of 100

nails and cement *b* and *c* respectively, are placed between the rest 3 and head member 5 and the article then inserted into a roll A, by first gripping the handle 4 and turning the spring 1 whereby to reduce its size for insertion into an opening *a* in a roll A, when the spring by frictional engagement with the wall of the opening *a* will act to frictionally hold the article in proper position. The cans or packages, therefore, will be suspended between the head member 5 and rest 3 and within the wall of the opening *a*, the straight stiffening portion 2 of the article lying between said cans or packages and the wall of the opening *a* against which it abuts, as shown in Fig. 1. During the turning of the upper end of the coil 1 to reduce its diameter, it will be seen that the end of the package acts to firmly hold the lower end of the coil, so that the reduction is effected without engagement of the coil with the circumferential wall of the bore of the roll.

It is pointed out that in order to release the packaged articles, held within the roll and supported by the retainer, that the coil 1 is reduced in diameter permitting the easy withdrawal of the retainer and articles from within the roll, and to avoid tearing or puncturing the paper by a sharp end of the rest 3, either because of the rest 3 moving off center or as a result of the packaged articles catching on the stiffening portion 2 and turning the rest 3, the end of the rest is looped or bent back on itself, as at 3', which gives the rest a smooth end and will thereby obviate such danger.

What I claim is:—

A package holding member for engagement in the bores of roofing rolls and the like, composed of an integral wire member having an elongated straight portion and substantially right angular ends whereby to grip and hold a package by and between said ends and straight portion, the outer of the ends being continued to form a coil spring of a diameter in excess of that of the bore of the roofing roll and terminating in a handle forming member which latter is disposed at the outermost end of the coil and is of a length to be gripped by the hand so as to turn the coils thereby to decrease the diameter thereof so as to enable the package to be easily inserted in the bore of the roofing roll, said elongated straight member and said right angular ends having such gripping relation to the package so as to hold the inner end of the coil fixed during turning of the handle forming member in decreasing the diameter of the coil both in insertion and removal of the member from the bore of the roofing roll.

WILLIAM H. SOMMER.
